UNITED STATES PATENT OFFICE.

ARTHUR LIPSCHUTZ, OF ST. LOUIS, MISSOURI.

JOURNAL-BOX LID.

No. 813,504.

Specification of Letters Patent.

Patented Feb. 27, 1906.

Application filed September 20, 1905. Serial No. 279,219.

To all whom it may concern:

Be it known that I, ARTHUR LIPSCHUTZ, a citizen of the United States, residing at the city of St. Louis, in the State of Missouri, have invented a certain new and useful Journal-Box Lid, of which the following is such a full, clear, and exact description as will enable any one skilled in the art to which it appertains to make and use the same, reference being had to the accompanying drawings, forming part of this specification.

My invention relates more particularly to a lid or cover for journal-boxes of the type usually employed on railway-cars, and has for its object to provide a box adapted to be closed as completely as possible against the admission of dust or other objectionable matter.

In the drawings, which show a journal-box and lid embodying my invention, Figure 1 is a longitudinal section of the box with the lid attached. Fig. 2 is a cross-section of the lid on the line 2 2 of Fig. 5. Fig. 3 is a cross-section of the lid on the line 3 3 of Fig. 5. Fig. 4 is a horizontal section on the line 4 4 of Fig. 1; and Figs. 5 and 6 are, respectively, a front and rear elevation of the lid.

Like characters of reference refer to similar parts in the different views. 10 is the journal; 11, the brass; 12, the key, and 13 the journal-box, provided with the usual opening 14. At the upper edge of this opening the box is provided with two perforated lugs 15, which constitute the hinge-pin lugs for the lid. Between these two lugs is formed a flange 16, grooved on its inner side, as shown at 17, for the passage of the hinge-pin. This flange extends upward, as best shown in Figs. 1 and 4, beyond the top of the 40 lugs 15 and laterally over or across the top of said lugs, as best shown in Fig. 4. The lid 20 is provided with two openings 21. A hinge-pin 22 passes through these openings and through the perforations in the lugs 15, 45 traversing the groove 17 in the rear face of the flange 16, and is secured in position by means of the usual cotter-pin 23. The lid is also provided with the usual forwardly and upwardly extending portion 25, the rear edge of 50 which is curved downward to form a lip 26. The lid is also provided with a spring 28, secured thereto by means of a rivet 29, set in a yoke 30, formed integral with the lid and beneath which the spring 28 passes. The lower 55 end of the spring 28 is bent to form a hook 31,

the outer end of which engages with a notch 32 adjacent to the opening 14 of the box to form a lock. 27 is a second yoke, also formed integral with the lid and embracing the hook 31, for which it acts as a stop. The lid is also 60 provided with a rib 33, which conforms to the shape of the opening 14 of the box.

When the lid is detached from the box, the upper end of the spring 28 occupies the position shown in full lines in Fig. 2; but when 65 the lid is in closed position on the box the upper end of this spring 28 occupies the position shown in full lines in Fig. 1 and in dotted lines in Fig. 2 and tends to hold the lid closed. The lid is also held closed by the 70 engagement of the hook 31 at the opposite end of this spring in the notch 32. It will be seen from an inspection of Fig. 1 that when the lid is in closed position the lip 26 on the lid is in contact with the inner or rear face of the 75 flange 16, which is extended upward to a sufficient extent to insure the closing of the box at this point, thus preventing the entry of dust. At the same time the hook 31 insures the firm engagement of the lid with the box. 80 When the lid is raised, the stop 27 engages the hook 31 and forces it from the notch 32, thus unfastening the lid.

It will be seen that by means of this construction the hinge-pin is exposed to view on 85 the rear face of the flange at the top of the box, thus permitting ready inspection to ascertain whether the pin has been broken.

Having fully described my invention, what I claim as new, and desire to secure by Letters Patent of the United States, is—

1. The combination with a journal-box provided with an opening, of a lid for said opening, a spring carried by said lid and bearing at one end against said box, the other end 95 of said spring engaging with said box to hold said lid in position.

2. The combination with a journal-box provided with an opening, of a lid for said opening, a spring carried by said lid and bearing at one end against said box, the other end of 100 said spring forming a lock engaging with said box to hold said lid in position, and a stop for said spring adjacent to said lock.

3. The combination with a journal-box 105 provided with an opening, of a lid for said opening, a spring carried by said lid and bearing at one end against said box, means securing said spring to said lid at a point intermediate the ends of said spring, the opposite end 110

of said spring engaging with said box adjacent to said opening to hold said lid in position.

4. The combination with a journal-box,
5 provided with hinge-pin lugs and a flange on
said box between said lugs, said flange being
provided with a groove on its rear face, of a
hinge-pin passing through said lugs and
groove, a lid journaled on said hinge-pin and
10 provided with a lip making contact with said
flange, and a spring carried by said lid and

bearing at one end against said box, the opposite end of said spring engaging with said box to hold said lid in position.

In testimony whereof I have hereunto set 15
my hand and affixed my seal in the presence
of the two subscribing witnesses.

ARTHUR LIPSCHUTZ. [L. S.]
